UNITED STATES PATENT OFFICE.

EDWIN FREEMAN, OF NORTON, MASSACHUSETTS, ASSIGNOR TO CORK AND LEATHER TOP ROLL COMPANY, OF PROVIDENCE, RHODE ISLAND.

IMPROVEMENT IN TOP-ROLLERS FOR SPINNING.

Specification forming part of Letters Patent No. 131,432, dated September 17, 1872.

To all whom it may concern:

Be it known that I, EDWIN FREEMAN, of Norton, in the county of Bristol and State of Massachusetts, have invented a certain new and useful Improvement in Top-Roller for Spinning.

My invention consists in a novel covering for top-rolls to be used either as an exterior drawing-surface or as a foundation for the leather covering ordinarily applied, composed of granulated wood, the particles of which are united with a suitable adhesive substance, and which may either be applied in sheets to the roll or molded thereon; and I do hereby declare that the following specification, taken in connection with the drawing furnished and forming a part of the same, is a clear and true description of rolls embodying my invention, and a desirable method of making the same.

Figure 1 represents, in perspective, one of my improved top-rollers provided with a leather covering. Fig. 2 represents the same in cross-section, and Fig. 3 represents one of my improved top-rollers provided wholly with the compound-cork covering.

It is to be understood that my roll in its general structure, does not differ from rolls long in use. I use the same metallic shell, and, when covered with leather on a foundation composed of the granulated-wood compound, its appearance differs only from other leather-covered rolls in common use in having exposed at each end, in section, the layer of the woody compound. The said compound is preferably composed of granulated cork-wood or cork-dust, the particles of which are united into a comparatively solid but elastic mass by any suitable adhesive matter.

In practice it is found that, say, twenty pounds of granulated cork-wood soaked in bisulphide of carbon and combined with five pounds of virgin caoutchouc, rendered fluid by the same solvent, (the latter being applied in sufficient quantity to the mass to render it sufficiently plastic,) will produce a compound well suited for the purpose. It should be evenly spread, while soft, upon any suitable light-woven textile fabric of flax or cotton, and, while drying, subjected to sufficient pressure to secure proper solidity. After having been so prepared the "cork compound" is cut into

strips and wound squarely upon the metallic surface of the roller, and secured thereto with any of the well-known adhesive cements which have for many years been used in the art of covering rolls with leather. There are many of the numerous well-known solvents for caoutchouc which would undoubtedly serve as good a purpose as the bisulphide of carbon; but that is known to be a desirable solvent in this connection. It has not been deemed essential to combine with the caoutchouc the mineral matter usually employed in the process of vulcanization; if the gum should be vulcanized, however, it would not necessarily affect the practical value of the compound. Some of the lighter woods—as, for instance, poplar and white pine—can also be employed with approximate results, but the cork-wood is much to be preferred to any known to me, and is as cheap as any other, as the refuse of bottle-cork establishments can be procured in desirable quantities at low cost. Among the several varieties of the article known as "Kamptulicon" or "cork carpet" (an article of English manufacture) there are several kinds well suited to the purpose, and they can be obtained at a cost so low as to render it unnecessary even to manufacture the compound expressly for the purpose of roll-covering. I am, however, unable to designate by any special term the particular kinds of "Kamptulicon" so suited, or to so describe them that they can readily be distinguished by their appearance from others which are not so well adapted to the use. In molding the compound upon the roll it is necessary to have a mold made in section, with which the desired degree of pressure can be attained. To secure proper unity between the compound to be molded and the metal, a wrapper of twine saturated in the solvent is first applied. Whether molded or applied in the sheet form it is desirable always to put the roll thus covered into a lathe and to grind off the covering to a uniform thickness, whether said covering is to be employed as an exterior drawing surface, or as a foundation for the usual leather clothing.

Cork-wood, in sliced sheets, has hitherto been employed with good results, both as an exterior covering and as a foundation for leather; but as the cork-wood so used is necessarily of

the most expensive quality, and as the pieces must be specially selected, it involves considerable expense which my invention obviates. Moreover, however carefully cork may be selected, it is difficult to avoid the hard solid spots which frequently occur therein, and any lack of uniformity in the density of a top-roll covering will result in its imperfect operation. By granulating the woody matter and then incorporating it into a comparatively solid, well-mixed mass with adhesive matter, an average degree of elastic solidity is attained, which is practically more uniform in its character than the natural cork-wood can possibly be.

Having thus described my invention, I claim as new and desire to secure by Letters Patent—

As an improved article of manufacture, a top-roller for spinning, the covering of which is composed wholly or in part of a layer or layers of a compound of adhesive gums and granulated cork or other suitable woody matter, substantially as described.

EDWIN FREEMAN.
